(57) **CLAIM**

We claim the ornamental design for a vacuum cleaner accessory brush, as shown and described.

DESCRIPTION

FIG. 1 is an isometric view of a vacuum cleaner accessory brush showing our new design;

FIG. 2 is a front elevation view thereof, the rear view being a mirror image;

FIG. 3 is a right elevation view thereof, the left side being a mirror image;

FIG. 4 is a top plan view thereof; and,

FIG. 5 is a bottom plan view thereof.

1 Claim, 4 Drawing Sheets

FIG. 1

FIG. 2

FIG. 3

FIG. 4

FIG. 5
